AUTOMATIC GUNSIGHT

Stephen L. St. Palley, Dalton, Mass.

Application November 7, 1958, Serial No. 772,553

2 Claims. (Cl. 88—2.2)

This invention relates to gun sights and is a continuation in part of my prior application Serial No. 689,349 filed on October 10, 1957, now abandoned.

It is known that the gravitational drop of a missile shot out from a gun increases rapidly with the distance traveled by the missile, so that the farther the target is the greater the angular elevation of the barrel of the gun must be to hit the target. The customary method of compensation for the gravitational drop of the trajectory is to employ a sighting device which is angularly adjustable with respect to the barrel and the usual practice is to adjust the angle of the sighting device so that the vertical drop from the axis of the barrel to the line of sight, measured at the target, is equal to the gravitational drop of the trajectory at that point. This method obviously requires the adjusting of the gun sight every time the target distance is changed which, under some conditions common in military application and in hunting, is not possible due to lack of time for making the adjustment.

The principal object of my invention is to provide a gun sight which, by the simple action of the sighting of the target, will automatically position the barrel of the gun so as to compensate for the gravitational drop of the trajectory at widely varying target distances without the need of making any adjustment on the gun sight, thereby making possible the rapid and accurate aiming of the gun at rapidly varying target distances.

Another important object of my invention is to provide a gun sight which is firmly attached to the gun barrel, without the customary angular adjustment and locking mechanism, thereby offering a construction of great simplicity and manufacturing simplicity.

A further object of my invention is to provide a gun sight which can be easily adapted to guns of all types having widely varying missile velocities and effective target ranges.

Other objects and advantages of my invention will be apparent during the course of the following description.

In the accompanying drawing, forming a part of this application, wherein for the purpose of illustration is shown a preferred form of my invention.

Figure 1 is a sectional view of the optical unit and the cross hair panel employed in the preferred form of my gun sight.

Figure 2 is a rear elevational view of the optical unit.

Figure 3 is a rear elevational view of the cross hair panel.

Figure 4 is a longitudinal sectional view of my gun sight mounted on the gun barrel.

Referring to the drawing, the numeral 1 designates the optical unit of my gun sight, which may be made of plastics, glass, or other suitable transparent material.

In the preferred form, shown in Fig. 1 and 2, this optical unit 1 is cylindrical in shape, with a geometric axis 5, and has a convex spherical front surface 2, and a concave spherical rear surface 3. Passing through the centers of these spherical surfaces 2 and 3, is the optical axis 4, a

2

straight line which, in this form, is parallel to said geometric axis 5, and is disposed in the same vertical plane.

The optical characteristics which make the advantageous and novel operation of my gun sight possible, are obtained by the special dimensioning of the optical unit 1.

In the design of convex-concave lenses it is known that by the use of the Steinhardt Cone formula it is possible to coordinate the curvatures of the spherical convex and concave surfaces and the axial thickness of the lens so as to obtain predetermined positive or negative dioptric values. The lenses thus dimensioned have prismatic power; they will deflect the ray of light, toward the optical axis in case of positive dioptric value, and away from the optical axis in case of negative dioptric value. These lenses possess the important characteristic, utilized in the present invention, that the angle of deflection of the light ray in these lenses vary with the decentration of the light ray measured from the optical axis of the lens.

In order to measure the decentration of the light ray, the concave rear surface 3 of the lens is provided with a vertical hair line 6, passing through the optical axis 4 and through the geometric axis 5, and with horizontal hair lines 7, 8, and 9, disposed at various predetermined decentrations from the optical axis 4, as illustrated in Fig. 2. Disposed coaxially at some distance from the rear surface 3 of the lens is the cross hair panel 10 (see Figs. 1 and 3) which has a similar vertical hair line 16 intersecting the optical axis 4 and the geometric axis 5, and horizontal hair lines 17, 18, and 19 located at the same decentrations as the corresponding horizontal hair lines on the rear surface 3 of the lens.

In Fig. 1 the dotted lines represent aiming light rays passing through the vertical hairlines 16 and 6 (see Figs. 2 and 3) at different decentrations. The light ray passing through the horizontal hairlines 17 and 7 will enter the optical unit 1 and will be deflected. In the example illustrated the optical unit 1 is so designed as to have a positive dioptric value, therefore, the aiming light ray 17, 7 will be deflected toward the optical axis 4, at an angle of deflection determined by the decentration of this 17, 7 light ray from the optical axis 4. Similarly, the light ray passing through 18 and 8 (see Fig. 1) will also be deflected toward the optical axis 4, but at a greater angle due to its greater decentration. The light ray through 19 and 9, being the farthest away from the optical axis 4, will have a still greater angle of deflection. It is characteristic in my invention that the aiming light ray is varied in decentration, but its direction between the optical unit 1 and the cross hair panel 10 is always parallel to the optical axis, also, that the angle between the optical axis and the deflected aiming light ray increases with the decentration of the light ray.

Fig. 4 illustrates the assembled gun sight mounted on the barrel. The optical unit 1 and the cross hair panel 10 are enclosed in a sight tube 11, which is secured to the gun barrel 13 by the rigid connection 12, so that the optical axis 4 and the geometric axis 5 of the gun sight are strictly parallel to the axis of the bore of the barrel, designated by 14. The arrow adjacent to the axis 14 indicates the direction of the travel of the missile in the barrel 13. Thus in the mounted gun sight the optical unit 1 is disposed toward the target, and the cross hair panel 10 toward the eye of the operator.

The operation of my gunsight is as follows:

The operation of my gun sight is based on the important characteristic of my optical unit 1 that the deflection of an aiming light ray passing through it varies with the decentration of the aiming light ray measured from the optical axis of the optical unit 1. This means that by the proper selection of the decentration it is possible to find an aiming light ray, in the plane defined by the vertical hair lines 6 and 16, which has a prede-

terminated angle of deflection. As in the example illustrated in Fig. 4 the optical axis 4 is parallel to the axis of the barrel 14 and as the aiming light rays entering the rear surface 3 of my optical unit 1 are also parallel to axes 4 and 14, it will be possible with my device to find an aiming light ray, in the plane of the vertical hair lines 6 and 16, by the proper selection of the decentration, which ray forms a predetermined angle, after deflection, with axis of the gun barrel 14.

The selection of the decentration of the aiming light ray is accomplished by the help of the horizontal hair-lines of the optical unit 1 and of the cross hair panel 10. These hair lines are calibrated in the following manner: Let us assume that the effective target range of the gun is from 50 ft. to 150 ft. and the curve of the trajectory is known. The first step is to determine the gravitational drop of the trajectory at 50 ft. target distance. This gravitational drop divided by the target distance gives the tangent of the elevation of the gun barrel required for 50 ft. target distance. The next step is to calculate from the optical data of the optical unit 1 the decentration at which the aiming light ray has the angle of deflection equal to the angle of elevation obtained for 50 ft. The calculated decentration will give the location of the calibrated horizontal hair line to be used for 50 ft. target distance. By the same method the required decentration of the aiming light ray and of the corresponding horizontal hair line can be determined for 150 ft. and also for one or more intermediate target distances. Finally the horizontal hair lines are marked on the posterior surface of the optical unit at the above calculated decentrations, measured from the optical axis 4, as shown in Fig. 2, and then the corresponding horizontal hair lines are marked on the crosshair panel 10 at the same calculated decentrations, as shown in Fig. 3.

Let us assume that in the example illustrated in the drawing the horizontal hair lines 7 and 17 correspond to the 50 ft. target distance, the horizontal hair lines 9 and 19 correspond to the 150 ft. target distance, and the lines 8 and 18 to an intermediate target distance. With this calibration of my gun sight the aiming at a target distance of 50 ft. merely consists of holding the gun so that the target appears at the intersection of the hair lines 16 and 17 of the crosshair panel 10, and the lines 6 and 7 coincide with the lines 16 and 17, respectively. In general, the aiming with my gun sight at any calibrated target distance is performed by bringing the image of the target in line with the corresponding cross hairs of the optical unit and the cross hair panel. The expert user of the gun knows how to estimate the target distance instantly by sight; with my gun sight he will soon learn to associate the target distance with the corresponding hair lines of my gun sight, and to interpolate between the

calibrated hair lines, and thereby will be able to perform accurate and rapid aiming at fast varying target distances.

It's to be understood that the form of my invention herein described and illustrated is only an example of the same and that various changes in the size, shape, and arrangement of parts may be resorted to, without departing from the spirit of my invention or the scope of the subjoined claims.

I claim:

1. A sighting device for a gun having a barrel, comprising a transparent optical unit having a convex spherical front surface and a concave spherical rear surface, defining an optical axis, said unit being dimensioned to have predetermined dioptric power so as to deflect the light ray at predetermined variable angles at corresponding variation of the decentration of said ray from the said optical axis, said optical unit being provided with a vertical hair line passing through said optical axis and with horizontal hair lines located at various distances from said optical axis; a cross hair panel, disposed perpendicularly to said optical axis adjacent to said concave rear surface of the optical unit, and being provided with a vertical hair line passing through said optical axis, and with horizontal hair lines located at the same distances, as the corresponding horizontal hair lines of the said optical unit, from said optical axis; a sight tube enclosing and firmly supporting said optical unit and said cross hair panel, and being firmly secured to said barrel so as to maintain a permanent angular and positional relation between said barrel, optical unit and cross hair panel.

2. A gun sight for mounting on the barrel of a gun, comprising, a transparent optical unit having convex spherical front surface and concave spherical rear surface, with an optical axis passing through the center points of said spherical surfaces, said optical unit being dimensioned so as to deflect the light ray at various predetermined angles when the decentration of said light ray, measured from said optical axis, is varied correspondingly, the rear surface of the said optical unit being provided with a vertical hair line passing through the said optical axis, and with horizontal hair lines located at various decentrations from said optical axis; a cross hair panel located adjacent to said rear surface of the optical unit and being provided with a vertical hair line passing through said optical axis, and with horizontal hair lines located at the same decentrations from said optical axis, as the corresponding horizontal hair lines of said optical unit; support means secured to said barrel, mechanically connecting the said barrel, optical unit and cross hair panel in a permanent angular and positional relation.
